BEAM COMPASS

Samuel Albert Nauheim, Flushing, N. Y.

Application October 22, 1947, Serial No. 781,397

4 Claims. (Cl. 33—27)

1 This invention relates to drafting instruments and more particularly to beam compasses.

Where a rigid beam compass is to be used for drawing a wide range of radii, it must either be of dimensions much greater than required for drawing smaller radii or it necessitates the use of attachments to be applied or removed depending on the radius to be drawn, all of which involves cost and inconvenience, and yet does not afford an instrument useful by the pattern maker or machinist for inscribing an arc upon a surface parallel to or at right angles to that of the center point from which the arc is struck.

It is accordingly among the objects of the invention to provide a device of the above type that is light in weight, compact and sturdy, comprising relatively few parts that are inexpensive and simple to manufacture without the need for close precision of workmanship, that is not likely to become out of order, and which admits of inscribing arcs upon a surface at right angles or parallel to the surface upon which the pivot point of the compass is placed, by means of which a set of concentric circles of slightly different radius may be readily drawn without disassembling the device or manually loosening any parts thereof, and that can be used to inscribe arcs having a large radius, and yet may be collapsed into a small space for ease in handling.

According to the invention, the device comprises a plurality of identical, channeled, slotted beams or bars preferably at least three in number, connected end to end in lapped relation through said slots so as to be pivotally and adjustably joined. Identical holders are provided, each having a substantially rectangular slide with a laterally extending mounting block unitary therewith in which a marking device such as a pencil or pen or a pivot point may be affixed to extend at substantially right angles to the bar. The base of that holder whose block mounts the pen or pencil is assembled in the channel of a bar with the pen or pencil carrying mounting block protruding laterally from the bar and, therefore, while held against pivotal displacement, is adjustable lengthwise of said bar for setting the radius. The base of the duplicate holder whose block mounts the pivot point, is assembled in the channel of a bar with the pivot point carrying mounting block overlapping the end of said bar and is thus fixed and non-adjustable in position.

In the accompanying drawings in which are shown one or more of various possible embodiments of the several features of the invention,

Fig. 1 is a side elevational view of the device

2 partly in cross-section with the holders in extreme position.

Fig. 2 is a perspective view of one of the component channel bars,

Fig. 3 is a top plan view taken along line 3—3 of Fig. 1.

Fig. 4 is a side elevational view of the device in collapsed position,

Fig. 5 is a fragmentary top plan view of the device utilizing five sections,

Figs. 6 and 7 are perspective views of the device illustrating two of its possible uses,

Fig. 8 is a detail perspective view of the device on a larger scale showing a holder, preferably for a pivot point affixed to the end of one of the channel bars, and

Fig. 9 is a view similar to Fig. 8 showing a holder, preferably for a marking device, slidably affixed in the channel of the channel bar.

Referring now to the drawings, the device comprises a plurality of identical sections, each comprising a beam or bar 11 of wood, metal, composition or the like, in the form of a channel section to provide maximum strength with minimum weight, and which has a longitudinal slot 12 therethrough extending nearly to the ends of the bar.

In the embodiment shown in Figs. 1, 3 and 4, three identical bars 11 are used, numbered 13, 14 and 15 and positioned so that bar 14 and bars 13 and 15 are in base to base relationship with the base of each of the latter two bars engaging the base of intervening bar 14. The bars are held together with standard fasteners, each of which, as shown herein, comprises a bolt 16 which extends through the slots 12 of the juxtaposed bars 13, 14 and 15. A washer 16' encompasses each of said bolts 16 and is retained by the head thereof between the side walls of the channel bars 13 and 15 respectively. A nut 19, preferably a wing nut as shown, having an elongated shank 19' which extends between the side walls of channel bar 14, is threaded on each of said bolts which desirably has an encompassing washer 18' and serves rigidly to clamp the bars together when tightened, yet affords a convenient means for enabling the bars to be adjusted with respect to each other.

Affixed to the free ends of bars 13 and 15, respectively, as shown in Figs. 1, 3 and 4, is a holder 20 for the pivot point 21 and holder 20² for a marking device such as a pencil, a pencil lead or a pen, and is illustratively shown as a pencil at 22.

As shown in Figs. 8 and 9, each of the holders

20' and **20²** which preferably are identical, comprises a substantially rectangular slide **23** of width slightly less than the channel **24** in each of said bars so as to fit therein.

Unitary with the slide **23** and extending laterally therefrom is a mounting block **27**, preferably equal in thickness to the base of the channel bar and which has an opening therethrough transversely of the length of the slide and parallel to the face thereof, in which the pencil **22** or pivot point **21** may be inserted to be retained therein by set screw **28**.

The holder is retained against the bar by means of a bolt **25** which extends through a washer **25'** and an opening in the slide **23** and through slot **12** in the bar, a wing nut **26** coacting with the end **26'** of the bolt rigidly clamping slide **23** in said channel.

By reason of the fit of the slide **23** in the channel, even when wing nut **26** is loosened with respect to the bar, the side walls of the channel prevent rotation of the holder about its retaining bolt **25** and consequently the substantially upright position of the pencil or pivot therein is not disturbed. In Fig. 8 the holder **20'** which preferably mounts the pivot point **21**, is shown affixed to the end of one of the channel bars with slide **23** lying in channel **24** and laterally extending block **27** abutting against the end of the channel bar as at **29** and flush therewith. In this position, with wing nut **26** tightly screwed on bolt **25**, the holder is rigidly fixed in place and cannot be moved along the channel bar even though wing nut **26** should be loosened. In Fig. 9, the holder **20²** which preferably mounts the marking device **22**, is shown mounted on one of the channel bars, with slide **23** lying in channel **24** and block **27** extending laterally from the channel bar. Thus, by merely loosening wing nut **26**, the holder may be moved to any desired position on the bar.

Although the device shown in the drawings preferably has a minimum of three bars, it is within the scope of this invention to provide a beam compass of the above type having only one bar with the holders heretofore described affixed thereon as previously set forth. With such a single bar beam compass, circles and arcs of relatively small radius could be drawn. By utilizing at least two bars, as shown in Fig. 6, it is possible to inscribe arcs with the pivot point on one surface and the marking device on another surface. It is of course to be understood that where a beam compass of greater length is desired than is possible to achieve with three bars, as shown in Figs. 1, 3 and 4, more bars may be added, as shown in Fig. 5.

Where an odd number of bars is used, such as is illustratively shown in Fig. 5 and they are assembled in base to base relation, an even number of bars would be in one plane and an odd number of bars in another plane. With the holders affixed to the bars (usually the extreme bars) in said latter plane, both the pivot point and pencil would lie in a common plane, and while this arrangement makes for convenience it is not vital to accuracy.

It is apparent that although large circles can be inscribed with this device, its construction is such that it can be folded into a compact package to facilitate carrying the same. To collapse the device, wing nuts **19** are loosened slightly and bars **13** and **15** are positioned (somewhat in the manner of a folding rule) in parallel relation and lateral engagement, with bar **14** diagonally thereacross, as shown in Fig. 4. The instrument

may conveniently be carried in a box or the like which may have extra bars and holders therein for the purpose hereinafter described.

In Figs. 6 and 7, two uses of the device are illustrated.

In Fig. 6 two surfaces at right angles to each other are shown numbered **31** and **32**. The beam compass which is illustratively shown with two bars, is assembled with bar **15** at right angles to bar **14**. An additional pivot point holder **20**, identical with holders **20'** and **20²**, may be provided which, in conjunction with pivot point holder **20'** at the end of bar **14**, acts as an axis around which the device may be moved to inscribe an arc upon the surface **32**.

In Fig. 7 two surfaces **33** and **34** are shown which are parallel to each other. Illustratively four bars are used in this beam compass, upright bar **35** having been added. As shown, bars **13** and **14** rest on the lower surface **33**, bar **35** is at right angles thereto, and bar **15** is at right angles to bar **35**. A pivot point **21** is affixed in the holder **20'** at the end of the bar **13**. Another holder **21²** affixed to bar **14** carries a rod **36** with a rounded end which serves as a slide support for the device in its movement along surface **33**. Bar **15** carries holder **20²** in which a pencil **22** is affixed in such a manner that it will ride on surface **34**, thus to inscribe an arc thereon.

Where it is desired to draw a number of closely spaced concentric arcs or circles, the device utilizing three bars may be assembled, as shown in Fig. 1. After the initial arc or circle is inscribed, a slight downward pressure at a joint of the instrument, as for instance by tapping, will cause its length to be increased or a like upward pressure would cause the length to be decreased, all without slipping from the new setting, and another arc or circle can thus be drawn which will have a slightly greater or a slightly smaller radius as the case may be than the previous arc or circle. By repeating this procedure, a number of arcs or circles of progressively increasing radius can be drawn, limited by the maximum length of the beam compass.

Thus the device requires the fabrication of only two distinct elements, a slotted channel bar, illustratively of wood, metal or plastic, and a holder. These parts in any desired number, depending upon the use to which the device is to be put, may readily be assembled and set for the variety of uses above described.

By reason of the construction herein set forth, the various units do not have to be in perfect alignment as long as they are securely fastened to each other. Thus precision in manufacturing is not required and the cost is kept low.

The term "identical" as applied in certain of the claims to the beams or bars, and the same term as applied to the holders for the pivot point and marker respectively, is intended to signify that each may be made from an identical pattern or from identical molds.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A drafting instrument comprising three identical bars, each having a longitudinal channel therein slotted nearly throughout the entire length of the bar, means extending through the slots of adjacent bars for pivotally and adjustably connecting said three bars together in end to end lapped relation with one of said bars intervening between the other two bars, marking and pivot point holders mounted on said other two bars respectively in said channels, at least one of said holders being slidably mounted thereon, and means rigidly to retain said holders in position on said bars.

2. The combination set forth in claim 1 in which said holders are identical, each comprising a substantially rectangular slide and a mounting block unitary with said slide and extending laterally therefrom, and said pivot point holder is affixed to the end of one of the outermost bars with the slide portion of said holder lying in the channel and said laterally extending block abutting against the end of said outermost bar.

3. A drafting instrument comprising a plurality of bars, each having a longitudinal channel therein slotted nearly throughout the entire length of the bar, means extending through the slots of the bars for pivotally and adjustably connecting said bars together in end to end lapped relation, at least three holders for said instrument, said holders each comprising a substantially rectangular slide mounted in the channel of a corresponding bar, and a mounting block unitary with said slide and extending laterally therefrom, means rigidly to retain said holders in position on said bars, and a marking device for at least one of said holders, and a pivot point for each of the remaining holders.

4. A drafting instrument comprising at least

three bars, each having a longitudinal channel therein slotted nearly throughout the entire length of the bar, means extending through the slots in the bars for pivotally connecting said bars together with at least two of said bars both engaging the base of a third bar, three holders mounted on said instrument, said holders each comprising a substantially rectangular slide mounted in the channel of a corresponding bar, a mounting block unitary with said slide and extending laterally therefrom, at least one of said holders being slidably mounted, a marking device mounted on the mounting block of said slidably mounted holder, one of the remaining holders having a pivot point mounted in the respective mounting blocks thereof, and the other of said holders carrying a rod acting as a slide support and means rigidly to retain said holders in adjusted position on said bars.

SAMUEL ALBERT NAUHEIM.
